(57) CLAIM

The ornamental design for a sole for footwear as shown and described.

DESCRIPTION

FIG. 1 is a front perspective view of a sole for footwear
showing my new design;

FIG. 2 is an enlarged front view thereof;

FIG. 3 is an enlarged back view thereof;

FIG. 4 is a right side view thereof;

FIG. 5 is a left side view thereof;

FIG. 6 is a top view thereof; and,

FIG. 7 is a bottom view thereof.

The broken lines depict portions of the sole for footwear which form no part of the claimed design.

1 Claim, 7 Drawing Sheets
